UNITED STATES PATENT OFFICE.

ERNST HEILBORN, OF CHARLOTTENBURG, GERMANY, ASSIGNOR TO GENERAL ELECTRIC COMPANY, A CORPORATION OF NEW YORK.

SYSTEM OF ELECTRIC METERING.

1,142,425.

Specification of Letters Patent. Patented June 8, 1915.

Application filed July 25, 1912. Serial No. 711,410.

To all whom it may concern:

Be it known that I, ERNST HEILBORN, a subject of the King of Prussia, residing at Charlottenburg, Germany, have invented 5 certain new and useful Improvements in Systems of Electric Metering, of which the following is a specification.

My invention relates to systems of metering electrical energy, and particularly to 10 multiple rate systems in which the charge for energy consumed depends upon the quantity used and also upon the time of day during which the consumption takes place.

The load curve of the ordinary central 15 generating station shows a maximum demand for energy during the evening hours when a large amount of electricity is used for lighting purposes. During the other hours of the day the demand on the central 20 station is relatively very light. Obviously, it is most desirable that the load curve of the station be as uniform as possible. Such a result can be approached if consumers would use more energy during the period of 25 light load on the central station and would restrict the consumption of energy to as small a quantity as possible during the period of peak load.

The object of my invention is to provide a 30 system of metering which will tend to induce consumers to restrict to as small an amount as possible their consumption of energy during the period of peak load, and which will tend to encourage the consumption 35 of a large quantity of energy during the period of light load.

I propose to accomplish the object of my invention by providing a double tariff rate, a low rate and a high rate. During the period 40 of peak load on the station, the consumer will be charged for the energy which he uses at the low rate as long as his demand on the station does not exceed a predetermined amount. When the rate of consumption 45 of energy rises above this predetermined amount, the consumer will be charged the higher rate for the total energy consumed during the time his demand exceeds the fixed amount. During the period 50 of light load the reverse method of charging

will be employed, and the consumer will pay the high rate as long as his demand is below a predetermined quantity. When, however, the demand is above this quantity 55 the consumer will obtain his energy at the low rate. In this manner consumers are encouraged to use large quantities of energy during the light load periods, and induced not to use large amounts during the periods of peak load.

In carrying out my invention, I provide an electric meter having at least two registers. One of these registers indicates the energy consumed for which the low rate is to be charged, and another indicates the energy for which the high rate is to be charged. The change in registration from one register to the other is accomplished automatically by a relay responsive to a predetermined change in the amount of energy 60 being consumed or the consumer's demand. A time controlled device operates at predetermined periods to reverse the effect of this relay upon the changing mechanism for the registers. By this apparatus the total energy consumed during the period of light load when the demand is above a predetermined quantity is registered on the low rate 65 register as is also the total energy consumed during the period of peak load, when the demand is below a predetermined amount. On the high rate register is registered the total consumption of energy during the light load period, when the demand is below the predetermined amount, and also the total consumption 70 during the peak load period when the demand exceeds the predetermined quantity. The registers may have the same rate of registration in which case the rate charged for the energy registered on one 75 register will be higher than the rate charged for the energy registered on the other register. Or the registers may have different rates of registration so that one will register a larger consumption than the other for 80 the same actual amount of energy consumed, in which case the rate charged will be the same for the energy registered on both registers.

The novel features which I believe to be 100

characteristic of my invention will be definitely indicated in the claims appended hereto.

The features of construction and mode of operation will be understood by reference to the following description taken in connection with the accompanying drawings which show a practical embodiment of my invention, and in which,—

10 Figure 1 illustrates diagrammatically one embodiment of the novel features of my new system of metering, and Fig. 2 is a modification thereof.

Referring to Fig. 1 of the drawings there is shown an electric meter 5 having the usual rotatable shaft and driving worm 6. The meter is placed in an electric supply circuit to measure the energy supplied by a source of electricity 7 to electric translating devices 8. Included in this circuit is a relay 9 which operates as a demand actuator. An armature 10 is in operative relation with the relay and when the current coil of the latter is energized the armature is attracted 20 and operates to close the contacts 11. A spring 12 normally holds the armature 10 so that contacts 11 are open and also provides a force to be overcome by the relay before contacts 11 can be closed. The amount of this opposing force of the spring 25 can be adjusted by the set screw 13. A scale 14 and coöperating pointer 15 may also be provided so as to readily and accurately make this adjustment in known units. By this arrangement the contacts 11 will be automatically closed when a predetermined current flows in the coil of the relay. An electromagnet 16 is provided with two sets of windings 17 and 18. The 30 circuit of the windings 17 is controlled by the contacts 11. The circuit of the winding 18 is controlled by the time switch 19. The time switch 19 may be of any desired construction. I have merely represented this 35 switch in a diagrammatic manner in the accompanying drawings and have shown a movable contact 29 mounted on the hour hand of a clock and arranged to coöperate with a sector shaped fixed contact 30 to 40 close the circuit of the winding 18 for a predetermined interval of time. The windings 17 and 18 are so arranged that their magnetic effects are opposite. Thus when the circuit of either winding is closed the 45 magnet 16 is energized, but when the circuits of both windings are closed the magnet is deenergized since one winding neutralizes the other. The electromagnet 16 has a coöperating armature 20. A spring 50 21 normally holds the armature in the position shown in Fig. 1. Operatively connected to the armature is a link mechanism 55 pivoted at 23 which controls the movement of a movable gear member 24. This 60 65 70 75 80 85 90 95 100 105 110 115 120 125

gear member is adapted to mesh with the worm 6 at all times, and also, according to its position, with either the driving gear 25 of register 26, or driving gear 27 of register 28.

The operation of my novel system of metering, as just described, is as follows: The set screw 13 is adjusted by aid of the calibrated scale 14 and pointer 15 so that the contacts 11 will be closed when a certain predetermined current flows in the circuit 75 of relay 9. Normally the spring 21 holds the armature 20 in the position shown in Fig. 1, and the movable gear member 24 is operatively connected to the high rate register 26. When the energy being consumed 80 in the translating devices 8 reaches a predetermined quantity the relay 9 automatically operates to close the contacts 11, and thus the circuit of the winding 17 is completed and electromagnet 16 is energized. 85 Armature 20 is then attracted by the poles of the electromagnet and operates to move gear member 24 from engagement with driving gear 25 into engagement with driving gear 27. The total energy consumed in 90 the translating devices is now registered on the low rate register 28.

The foregoing description of the operation of my system of metering is correct only when no current is flowing in the winding 18. The circuit of this winding is closed by a time switch during the period of peak load on the central station. When the circuit of winding 18 is thus closed its effect will be to neutralize the effect of winding 17. In this way when the demand is below a predetermined quantity the contacts 11 will be open and the electromagnet 16 will be energized by winding 18. Movable gear 24 will thus be in operative relation with the low rate register 28. If the demand during this peak load period rises above the predetermined quantity the circuit of winding 17 will be closed, and since the effect of one winding is to neutralize the effect of the other, the electromagnet 16 will be deenergized, and the energy consumed in the devices 8 will be registered on the high rate register 26. It will thus be seen that the effect of the time switch 19 and winding 18 is to reverse the normal effect of the winding 17 upon the register changing mechanism.

In Fig. 1, I have shown the demand actuator provided with two windings. One winding is included in series relation with the circuit of the translating devices 8, as heretofore described, and the other winding 18' is in series with the winding 18 of electromagnet 16. The circuit of winding 18' is, therefore, completed by the time switch 19 during the period of peak load. In this manner the winding 18' will operate during

the period of peak load to increase or decrease, according as the winding 18' opposes or aids the normal series winding of relay 9, the predetermined demand at which 5 armature 10 will be attracted and the contacts 11 closed.

In case it is not desired to have a different predetermined demand during the period of peak loads the winding 18', shown in 10 Fig. 1, may be omitted. This modification of my invention I have illustrated in Fig. 2 of the drawings. In this figure the relay or demand actuator 9' has only one winding which is the same as the series winding described in connection with relay 9. The winding 18 of the electromagnet 16 is, accordingly, arranged to be connected directly across the line by means of the time switch 19. The other features of construction of 15 20 the modification illustrated in Fig. 2 are the same as heretofore described in connection with Fig. 1.

From the foregoing description it will be readily understood that during the period 25 of light load on the central station the circuit of winding 18 is open and the total energy consumed when the demand exceeds a predetermined amount is registered on the low rate register. When the demand 30 is below this amount the consumption is registered on the high rate register. During the period of peak load just the reverse takes place. The circuit of winding 18 is now closed and the total energy consumed 35 when the demand is below a predetermined quantity is registered on the low rate register, while that consumed when the demand is in excess of this quantity is registered on the high rate register.

40 I desire it to be understood that my invention is not limited to the particular construction or arrangement of apparatus here shown, since many changes which do not depart from the spirit of my invention, will 45 be obvious to those skilled in the art, and which changes are within the scope of the present claims.

What I claim as new and desire to secure by Letters Patent of the United States, is:— 50 1. The method of metering electrical energy which consists in registering upon one register during certain periods of time only the total consumption of energy when the demand is less than a predetermined quantity and during other periods of time only the consumption of energy when the demand is in excess of a predetermined quantity, and effecting such registration of energy by the magnitude of the demand.

55 60 2. The method of metering electrical energy which consists in registering upon one register during certain periods of time only the total energy consumed when the demand is in excess of a predetermined quantity and

during other periods of time only the total 65 energy consumed when the demand is less than a second predetermined quantity, registering upon a second register the remaining energy consumed during any period of time, and effecting such registration of energy 70 upon the appropriate register by the magnitude of the demand.

3. The method of metering electrical energy supplied by a central generating station to electric translating devices which 75 consists in registering upon one register during the period of peak load on the station only the total energy supplied when the demand is less than a predetermined quantity and upon a second register only the 80 total energy supplied when the demand is in excess of said predetermined quantity, registering at other periods of time upon the first mentioned register only the total energy supplied when the demand is in excess of a second predetermined quantity and upon said second register only the total 85 energy supplied when the demand is less than said second predetermined quantity, and effecting such registration of energy 90 upon the appropriate register by the magnitude of the demand.

4. A system of metering electrical energy comprising a meter, a plurality of registers for registering the energy metered, an electric supply circuit, means responsive to the electrical condition of said circuit for determining the register upon which the energy metered is registered, and means for reversing the effect of said means at predetermined times.

5. A system of metering electrical energy comprising a meter, a plurality of registers for registering the energy metered, an electric supply circuit, means responsive to a 105 predetermined change in the electrical condition of said circuit for determining the register upon which the energy metered is registered, and means for varying at predetermined times the predetermined change to 110 which said means is responsive.

6. A system of metering electrical energy comprising a meter, a plurality of registers for registering the energy metered, an electric supply circuit, means responsive to a 115 predetermined change in the electrical condition of said circuit for determining the register upon which the energy metered is registered, means for reversing the effect of said means at predetermined times, and means for varying at predetermined times the predetermined change to which said first mentioned means is responsive.

7. A system of metering electrical energy comprising a meter having a register, electric translating devices, means for registering on said register during predetermined times only the total energy consumed in

4
said translating devices when the demand is in excess of a predetermined amount, and means for registering on said register during other times only the total energy consumed in said translating devices when the demand is less than a predetermined amount.

8. A system of metering electrical energy comprising a meter having two registers, 10 electric translating devices, means for registering on one of said registers during certain periods of time only the total energy consumed in said translating devices when the demand is in excess of a predetermined 15 quantity, means for registering on the second register during said same periods of time only the total energy consumed in said translating devices when the demand is less than the predetermined quantity, means for 20 registering on said first register during all other periods of time only the total energy consumed in said translating devices when the demand is less than a predetermined quantity, and means for registering on the 25 second register during the last mentioned periods of time only the total energy consumed in said translating devices when the demand is in excess of the last mentioned predetermined quantity.

30 9. A system of metering electrical energy comprising a meter having a rotatable shaft and two registers, electric translating devices, a movable member for operatively connecting said shaft to either of said registers, means responsive to the quantity of energy being consumed by said translating devices for operating said movable member, and time controlled means for reversing the effect of said last mentioned means upon 40 said movable member.

10. A system of metering electrical energy comprising a supply circuit for electric translating devices, a meter having a rotatable shaft and two registers, a gear train 45 for each of said registers, a movable member for connecting either of said gear trains to the meter shaft, an electromagnet, an armature coöoperating with said electromagnet and operatively connected to said movable member, a time controlled winding for said electromagnet, a second winding for said electromagnet, and means responsive to a predetermined change in the electrical condition of said supply circuit for controlling 50 the circuit of said second winding.

11. A system of metering electrical energy comprising a meter having a rotatable shaft and two registers, an electric supply circuit, a movable member for placing said shaft in operative relation with either of said registers, an electromagnet, an armature coöperating with said electromagnet and operatively connected to said movable member, a winding for said electromagnet, a time con-

trolled switch for said winding, a second 65 winding for said electromagnet, a relay responsive to a predetermined change in the electrical condition of said supply circuit for controlling the circuit of said second winding, and adjustable means for predetermining the change to which said relay responds.

12. A system of metering electrical energy comprising a meter having a rotatable shaft and two registers, an electric supply circuit, 75 a movable member for placing said shaft in operative relation with either of said registers, an electromagnet, an armature coöperating with said electromagnet and operatively connected to said movable member, a winding for said electromagnet, a relay for controlling the circuit of said winding and having a current coil included in said supply circuit, a second winding for said electromagnet, a second winding for said relay, and 80 a time switch for controlling the circuits of said second windings.

13. A system of metering electrical energy comprising in combination an electrical installation, means for metering the electric 85 energy supplied to said installation, a register and means for registering on said register during certain periods of time the energy supplied to said installation only when the demand of the installation is less than a 90 predetermined quantity and during other periods of time the energy supplied to said installation only when the demand of the installation is in excess of a predetermined quantity.

14. A system of metering electrical energy comprising in combination an electrical installation, means for metering the electric energy supplied to said installation, a register, means for registering on said register 105 during certain periods of time the energy supplied to said installation only when the demand of the installation is less than a predetermined quantity and during other periods of time the energy supplied to said installation only when the demand of the installation is in excess of a predetermined quantity, a second register and means whereby the remaining energy supplied to said installation is registered upon said second 110 register.

15. A system of metering electrical energy comprising in combination an electrical installation, a source of electric energy supply, means for metering the electric energy supplied to said installation, two registers, means for registering upon one register during the period of peak load on said source the total energy supplied to said installation 120 only when the demand of the installation is less than a predetermined quantity and for registering upon the second register the total energy supplied to said installation only 125

when the demand of the installation is in excess of said predetermined quantity, and means coöperating with said last mentioned means for registering upon the first register during other periods of time the total energy supplied to said installation only when the demand of the installation is in excess of a second predetermined quantity and for registering upon the second register the to-

tal energy supplied to said installation only 10 when the demand is less than said second predetermined quantity.

In witness whereof, I have hereunto set my hand this 9th day of July, 1912.

DR. ERNST HEILBORN.
